UNITED STATES PATENT OFFICE.

ANDRÉ MARIE PASCAL RENÉ PIÉDALLU, OF SEVRES, FRANCE.

FUEL BURNER.

Application filed February 2, 1922. Serial No. 533,696.

To all whom it may concern:

Be it known that I, ANDRÉ MARIE PASCAL RENÉ PIÉDALLU, a citizen of the French Republic, of 11 Rue des Gerideaux, Sevres, 5 Seine-et-Oise, France, have invented a Fuel Burner, of which the following is a full, clear, and exact description.

This invention has for its object a burner utilizing as fuel mazout, coal oil or other 10 liquid or liquefiable fuel, this burner being so combined as to do away with the use of air under pressure.

The said burner, which is applicable to all 15 industrial or domestic furnaces or stoves; is essentially characterized by the application of nozzles of decreasing cross-section, so arranged as to permit the admission of atmospheric air and its distribution at an accelerated speed at various points of the combustion 20 chamber of the burner, viz:

(a) Admission of air for the ignition of the fuel;

(b) Admission of air above the ignited fuel for accelerating and completing the 25 combustion.

In order that the invention may be clearly understood it will be described hereafter with reference to the accompanying drawing, in which:

30 Fig. 1 is a front elevation.

Fig. 2 is a longitudinal vertical section made according to line 2—2 of Fig. 1.

Fig. 3 is a plan view.

Fig. 4 is a vertical cross section made according to line 4—4 of Fig. 2.

Fig. 5 is a front view of a modification.

Fig. 6 is a longitudinal vertical section made according to line 6—6 of Fig. 5.

Fig. 7 is a plan view of the cup.

40 As illustrated in the drawing, the burner forming the subject-matter of this invention, is composed of a cup 1 constituting the combustion chamber and between the edges of which is held a tube 2 adapted to pour in the cup 1 the fuel, mazout or the like, which is fed in the said tube 2 by a funnel 3.

This tube 2, which is freely open to the atmosphere at its front end is provided, at its opposite end, with a bottom 4 forming, 50 with the tube 2, an opening 5 permitting the flow of the fuel in the cup 1. This cup 1, which has the shape shown in the drawing, is provided on its front face with a flared opening constituting an atmospheric air intake, the conical wall 6 of which is connected with those of the cup by providing, below

the fuel inlet tube 2, an opening 7, of reduced cross section, having the shape of a crescent, putting in communication the interior of the cup 1 with the atmosphere and determining an acceleration of the speed of the air drawn in the said cup at the time of the ignition and during the combustion of the mazout or other fuel poured in the cup through the tube 2.

Above the tube 2 is arranged a second air intake the construction of which is such as to bring above the ignited fuel reheated atmospheric air.

This air intake is constituted by a kind of 70 branch 8 extending on the greatest part of the length of the cup 1 which it covers in such a manner that the lower wall of the said branch forms the top of the combustion chamber and that the said wall is exposed to 75 the action of the flames of the ignited fuel for thus highly reheating the air circulating in the branch 8; this branch is provided with an inlet opening of larger cross section than the distribution opening 10, for the purpose 80 of accelerating the circulation of the air.

At the rear part of the cup 1 is arranged an atmospheric air intake 11 which, as the previous ones, is so arranged as to bring the atmospheric air at an accelerated speed 85 above the ignited fuel.

Finally, the improved burner may accessorially be provided with a U-shaped tube 12, as illustrated in the drawing and the ends of which open in the atmosphere; the said 90 tube is provided with perforations 12^a for distributing also reheated air above the ignited fuel.

The above described apparatus operates in the following manner:

The fuel, mazout or the like, fed in the tube 2 flows in the cup 1 through the opening 5 provided at the rear of the said tube, this fuel is then ignited in the cup 1 which thus constitutes the combustion chamber.

The air necessary for the combustion is admitted from the exterior through the flared opening 6 the portion 7 of reduced cross section of this opening 6 causing the acceleration of the speed of the air, a certain quantity of air entering also into the combustion chamber through the tube 2. During the combustion, the gases and flames which lick the branch 8 heat the latter so that the atmospheric air circulating in this branch is brought to a high temperature and led at an accelerated speed above the ignited

fuel through the distribution opening 11 of reduced cross section.

Finally fresh additional air is admitted through the nozzle 11 and distributed by the latter above the ignited fuel so as to complete the combustion.

In order to permit of facilitating the ignition and to conveniently effect the cleaning of the burner, the cup carrying the tube distributing the mazout can be mounted in such a manner that it can be moved longitudinally by hand.

This arrangement is illustrated in Figs. 4 to 6, in which the said cup 1, provided as stated with the tube 2, has on its sides lugs 13 which are fitted in slideways 14 integral with the fixed support provided with the nozzles 8 and 11, the nozzle 8 distributing hot air and the other fresh additional air above the ignited fuel, as described with reference to Figs. 1 to 4.

Finally this support can be provided with a conduit 15 arranged above the ignited fuel and perforated with one or more rows of air inlet orifices. The operation is the same as that above described, except that the cup 1 is moved backward by hand in the slideways 14 by means of the handle 16, so as to release it from the support at the time of the ignition or after extinction for permitting its cleaning.

The above described arrangements are, of course, given by way of example only, the forms, materials and dimensions of the various constituent parts may be modified without departing thereby from the scope of the invention.

Claims:

1. A burner for liquid or liquefiable fuels, comprising a cup forming a combustion chamber,—a tube carried by the said cup for leading in the latter the liquid fuel,—a flared opening on the front face of the cup

for leading in the lower part of the latter the atmospheric air necessary for the ignition of the fuel and for imparting, at the same time, to this air an accelerated speed,—a nozzle of decreasing cross section, arranged above the said cup and adapted to take the atmospheric air and to lead it in a reheated condition and at an accelerated speed above the ignited fuel,—a nozzle of decreasing cross section arranged at the rear part of the cup and adapted to take additional atmospheric air and to lead it above the ignited fuel for completing the combustion.

2. A burner for liquid or liquefiable fuels, comprising a cup forming a combustion chamber,—a tube carried by the said cup for leading in the latter the liquid fuel,—a flared opening on the front face of the cup for leading in the lower part of the latter the atmospheric air necessary for the ignition of the fuel and for imparting, at the same time, to this air an accelerated speed,—a nozzle of decreasing cross section, arranged above the said cup and adapted to take the atmospheric air and to lead it in a reheated condition and at an accelerated speed above the ignited fuel,—a nozzle of decreasing cross section arranged at the rear part of the cup and adapted to take additional atmospheric air and to lead it above the ignited fuel for completing the combustion,—and means for moving the cup and the tube it carries for facilitating the ignition and the cleaning of the burner.

The foregoing specification of my "burner utilizing mazout or other liquid or liquefiable fuel, without pressure, capable of being fitted on any industrial and domestic heating apparatuses," signed by me this 19th day of January, 1922.

ANDRÉ MARIE PASCAL RENÉ PIÉDALLU.
